US00D643646S

(12) United States Design Patent
Buckles et al.

(10) Patent No.: US D643,646 S
(45) Date of Patent: * Aug. 23, 2011

(54) COOLER

(75) Inventors: John Buckles, Chicago, IL (US); Daniel Noe, Frisco, TX (US); Gregory Butz, Glenview, IL (US); Shereen Besselle, Bronx, NY (US); Adam Harter, Danbury, CT (US); Emad Jafa, Brewster, NY (US)

(73) Assignee: PepsiCo, Inc., Purchase, NY (US)

() Term: 14 Years

(21) Appl. No.: 29/378,858

(22) Filed: Nov. 10, 2010

(57) CLAIM

The ornamental design for a cooler, as shown and described.

DESCRIPTION

FIG. 1 is a front, right perspective view of a cooler showing our new design;

FIG. 2 is a top view thereof;

FIG. 3 is a front view thereof;

FIG. 4 is a right side view thereof;

FIG. 5 is a left side view thereof;

FIG. 6 is a rear view thereof;

FIG. 7 is a bottom view thereof; and,

FIG. 8 is a front, right perspective view.

The uneven-length broken lines represent unclaimed boundaries of the claimed design. The even-length broken lines showing the remainder of the cooler are for environmental purposes only and form no part of the claimed design.

1 Claim, 4 Drawing Sheets
